UNITED STATES PATENT OFFICE.

ALLEN HOWARD MIX, OF BURLINGTON, VERMONT, ASSIGNOR TO PORTER SCREEN MANUFACTURING COMPANY, OF BURLINGTON, VERMONT, A CORPORATION.

WINDOW-SCREEN.

No. 911,318.

Specification of Letters Patent.

Patented Feb. 2, 1909.

Application filed March 10, 1908. Serial No. 420,264.

To all whom it may concern:

Be it known that I, ALLEN HOWARD MIX, a citizen of the United States, residing at Burlington, in the county of Chittenden 5 and State of Vermont, have invented new and useful Improvements in Window-Screens, of which the following is a specification.

This invention relates to improvements in 10 window screens and similar adjustable or sliding closures; and one of the objects of the invention is to provide spring-pressed rollers for guiding and supporting the screen and compensating for variations to the side 15 of the frame due to climatic changes so as to maintain contact with the screen guides irrespective of contraction or expansion of the frame.

Another object of the invention is to provide 20 a screen having opposite sets of spring-pressed rollers, one of which sets is retractable to permit ready removal of the screen at any time.

A still further object of the invention is to 25 provide guide rollers having supporting and spring-projecting means of novel construction to insure an effective action thereof, and wherein the brackets are adjustably mounted to regulate the spring pressure and extent 30 of projection of the rollers.

The invention consists of the features of 35 construction, combination and arrangement of parts hereinafter fully described and claimed, reference being had to the accompanying drawings, in which:—

Figure 1 is an elevation of a window screen partly broken away and partly in section to show the spring supporting means for one of the rollers at each side thereof. 40 Fig. 2 is a horizontal transverse section through one of the guides and one side of the screen frame, on a line through the upper end of the roller bracket. Figs. 3 and 4 are vertical transverse sections on an enlarged scale showing the construction of the 45 screen and rollers at the opposite sides of the screen. Fig. 5 is an end elevation looking toward the side of the screen shown in Fig. 3.

Referring now more particularly to the

drawings, 1 designates the frame of a screen which may be in general of ordinary construction, and 2 designates the guides for the screen arranged in practice at the opposite sides of the window frame.

55

Each of the side bars 3 and 4 of the screen is provided with a desired number of spring-pressed rollers to bear and travel upon the adjacent guide 2. As shown, the side 3 is provided with a pair of such guiding and 60 supporting rollers, each of which is arranged within a recess 5 formed in said side and opening through the outer edge thereof. Each roller structure comprises a vertical supporting bracket 6 embodying spaced side 65 pieces 7 and a back wall or piece 8. The upper ends of the side pieces 7 project above the wall 8 in the form of apertured ears 9 providing supports for the journals of the guiding and supporting roller 10, while the 70 lower ends of said side pieces are extended below the lower edge of the back plate and formed with hooked portions 11 to engage the cross-bar of a staple 12 fixed to the bottom wall of the recess, by which the bracket 75 is pivotally mounted for swinging movement to project the roller 10 to a greater or less extent.

The upper end of the bracket is adjustably connected with the inner wall of the recess 80 by a screw 13 engaging said wall. This screw passes through an opening 14 in the back plate 8 and has its headed end 15 disposed to bear upon the front face of said plate and limit the outward movement of 85 the bracket. The unthreaded portion of the shank of the screw adjacent the head projects through the opening 14, which latter is of less area than the head of the screw but of sufficient size to permit unrestricted inward movement of the bracket, so that pivotal movement of the bracket within determined limits is permitted to adapt the roller 10 to bear firmly against the surface of the guide 2 and to conform to irregularities 90 therein. A substantially V-shaped spring 16 is provided to force the bracket outward. The arms of this spring lie respectively in front and in rear of the wall 8, the rear arm bearing at its free end against the inner wall 95 100

of the recess, while the free end of the outer or front arm engages a pin 17 supported by the side pieces 7, so that the pressure of the spring will be transmitted to swing the bracket outward and force the roller 10 with the desired pressure against the guide. The bight portion of the spring embraces and engages the lower edge of the wall 8, thus maintaining the spring in proper operative relationship to the coacting parts.

The rollers at the opposite side of the frame, namely, those mounted upon the side rail 4 to engage the opposite guide 2, are generally similar in construction to the rollers mounted upon the side rail 3, except that means are provided for use in connection with the brackets on the side rail 3 to permit retraction of said rollers from engagement with the guide, thus allowing the screen to be readily removed from the window frame when occasion requires. As shown clearly in Fig. 4, the adjusting screw 13^a has a threaded engagement with a tubular stem 18 arranged to slide in a bore or opening 19 formed in the side rail 4 and extending through the inner face of said rail to the inner portion of the recess 5. The outer end of this tubular stem is transversely recessed to receive a ring or other suitable grip 20 by which said stem may be drawn outward to pull the bracket inward against the resistance of the spring 16, by which the roller may be retracted or withdrawn from engagement with the adjacent guide 2, as will be readily understood. The screw 13 and stem 18 not only constitute an adjustable means for limiting the outward movement of the roller, but also provides an extensible retracting device which permits such adjusting action.

It will be seen from the foregoing description that the spring-pressed rollers at the opposite sides of the screen travel in contact with the guides 2 and permit ready up and down adjustment of the screen, and that such rollers permit the screen to be loosely mounted, as they maintain a constant pressure on the guides and are movable to compensate for any irregularities in the surfaces thereof, as well as to compensate for any variations in the width of the frame occurring from contraction and expansion as the result of climatic changes. The screen may be readily applied in position without removing the guides by inserting it with the retractable set of rollers retracted in an obvious manner, and may be as conveniently removed when occasion requires by withdrawing said retractable rollers from engagement with the adjacent guide. This construction not only secures the foregoing advantages, but also permits the guides to extend the full length of the window frame for adjustment of the screen to any position, as

the termination of the guides at any particular point to permit removal of the screen 65 is not necessary.

Having thus fully described the invention, what is claimed as new is:—

1. A screen provided with a recess, a bracket pivotally mounted at its lower end 70 within the recess and provided at its upper end with a roller, a doubled-leaf spring for forcing the bracket outward, said spring being carried by the bracket and having one of its arms bearing against a wall of the 75 recess, and means for adjustably limiting such outward movement of the bracket.

2. A screen provided with a recess, a bracket pivotally mounted at its lower end within the recess and provided at its upper 80 end with a roller, a doubled-leaf spring for forcing the bracket outward, said spring being carried by the bracket and having one of its arms bearing against a wall of the recess, and an adjusting screw engaging the 85 upper end of the bracket for limiting the outward movement thereof.

3. A screen provided with a recess, a bracket pivotally mounted at its lower end within the recess and provided at its upper 90 end with a roller, means connected with the upper end of the bracket for limiting the outward movement thereof, and a leaf spring having front and rear arms respectively bearing against a wall of the recess 95 and the bracket to force the latter outward.

4. A screen provided with a recess, a bracket pivotally mounted at its lower end within the recess and provided at its upper end with a bearing roller, a spring for 100 normally pressing the bracket outward to force the roller against the window frame, a member slidably mounted in the screen frame and connected with the upper end of the bracket whereby the latter may be retracted against the pressure of the spring, 105 and a finger piece connected with said member.

5. A screen provided with a recess, a bracket pivotally mounted at its lower end 110 within the recess and provided at its upper end with a bearing roller, said bracket having a back wall terminating at its lower end above the pivotal connection, and side walls, a cross-piece extending between said 115 side walls in advance of said back walls, a V-shaped leaf spring having its bight portion engaging the lower edge of the back wall and its arms respectively bearing against said cross-piece and the rear wall of 120 the recess, and means adjustably connecting the bracket with the screen frame to limit the outward movement of said bracket.

6. A screen provided with a recess, a bracket pivotally mounted at its lower end 125 therein and provided at its upper end with

a roller, said bracket having a rear wall and a cross piece arranged in advance of said wall, means connected with the upper end of the bracket for limiting its outward movement, and a V-shaped spring having its bight portion engaged with the lower end of said rear wall and its arms arranged respectively in front and rear of said rear wall and respectively engaging the rear wall

of the recess and said cross piece of the bracket to force said bracket outward.

In testimony whereof I affix my signature in presence of two witnesses.

ALLEN HOWARD MIX.
